Attorney

UNITED STATES PATENT OFFICE

LEONARD BRUCKLER, OF FOX CHASE, PENNSYLVANIA

ELBOW PROTECTOR

Application filed July 8, 1931. Serial No. 549,341.

This invention relates to apparel protectors and more particularly to a device effective to prevent the elbow portions of automobile drivers' clothing from injury and damage, 5 the primary object being to provide an elbow protector which is anti-frictional with respect to the parts with which it engages, or on which the arm rests while driving an automobile.

10 Another object is to furnish a device of the specified type which eliminates frictional injury to the upholstery of the wearer's car incident to rubbing movements, while permitting free action of the arm at the elbow section.

15 A further object is to provide a protector of the kind specified that positively safeguards the wearer's coat sleeve in the region of the elbow from becoming shiny and prematurely worn.

With these ends in view, and such others as are incidental thereto or may later on appear, my invention essentially consists in the details of construction and combinations of 25 elements hereinafter set forth and thereafter specifically designated in the subjoined claims.

20 I will now proceed to describe my invention in detail with reference to the accompanying sheet of illustrative drawings and the reference numerals appearing thereon.

In the drawings:—

Fig. 1 is a perspective view of my improved elbow protector in applied position.

35 Fig. 2 is a longitudinal section of the same.

Fig. 3 is a staggered-section, taken approximately as indicated by the arrowed line 3—3 in Fig. 2.

40 Fig. 4 is an exploded view, on a reduced scale, of the main components entering into the construction of my novel elbow protector; and,

Fig. 5 is an enlarged detail section hereinafter fully explained.

In the main my novel elbow protector comprises companion components 6, 7 and 8 of leather and textile fabric, the former serving as the outer covering or body and 50 the latter as the inner or lining portion of

the device. As best appreciated from Fig. 4 the leather components 6 and 7 are duplicates with notchings 9, for a purpose later on explained; while the component 8 includes securing bands or straps 10 attached thereto by 55 stitching 11; or, said straps may, obviously, be made an integral part of the component 8. Opposed notchings 12 are provided medially of the length of the component 8, while it is to be particularly remarked that 60 the longitudinal edges 13 of said component are opposingly curved, whereas the corresponding edges of the components 6, 7 are medially curved at 14 but merge into substantially straight or tangential portions 15. 65

The textile fabric components or lining elements 16, 17 and 18 are respectively similar in contour to the components 6, 7 and 8, and hence need no further detailed explanation herein, insofar as their form is concerned. 70

In assembling the leather components 6, 7 and 8, as well as the fabric parts 16, 17 and 18, thus far described, I initially place the notchings 9, 12 in registration and unite 75 the respective components, or parts, along their adjoining edges, as viewed in Fig. 4, by sewing, as conventionally indicated at 19 in the other views. Subsequently I retrovert the united edges at 20, Fig. 5 and seam 80 or hem them, as conventionally indicated at 21. As a result of the union of the parts, as just set forth, the medial leather component 8 becomes somewhat dished inwardly as best understood from Figs. 1 and 2, while 85 the components 6 and 8 are similarly curved longitudinally of their median line on the sides united to the center or inner component 8.

90 Centrally of the lining component 18 and to the inner face thereof I secure a pad made up of somewhat rectangular textile elements 22, 23 and 24, Fig. 5, of outwardly increasing dimensions relatively; said elements being united to the retroversions 20 of the 95 liner elements 16, 17 by quilting stitches 25, Figs. 2 and 5, in an obvious manner. Thus it will be readily seen and understood, the pad of elements 22—24 not only constitutes 100 a cushion for the wearer's elbow joint, but

that it is secured "free" and movable with respect to the outer built up leather body or covering. It is also to be noted that the lining component 18 has extensions 26, corresponding to and registering with the straps 10.

The structures thus far explained are next laid one upon the other and the surrounding edges around the body of the device, as well 10 as the edges of the straps, seamed together at 27, in a manner similar to fitting and securing a lining in a cap or coat whereupon the straps 10 are provided with conventional "snap" fasteners 28 whereby the device can 15 be adjusted to either a thin or a fat arm with ease.

From the foregoing the simplicity of my novel elbow protector will be self-evident and its advantages obvious to those acquainted with the art, hence it is thought further detailed explanation herein is not required.

Having thus described my invention what I claim is:—

1. An elbow protector for automobile drivers comprising an exterior covering of leather embodying a central component having opposingly curved longitudinal edges and flanking components of similar contour, the adjoining edges of said components being 25 sewn together and hemmed, a textile fabric lining of corresponding contour and formation united to the covering around the perimetric edges, a pad comprising elements having outwardly increasing dimensions secured 30 to the lining at the elbow region free of union with the covering, and means for detachably securing the device about the wearer's arm.

2. An elbow protector for automobile drivers comprising an exterior covering of leather embodying a central component having opposingly curved longitudinal edges and co-extensive strap portions, flanking components having the medial edges reversely curved with tangentially-mergent portions, 40 the adjoining edges of said components being sewn together and hemmed, a textile material lining of corresponding contour and formation united to the covering around the perimetric edges of the components and strap 45 extensions, a pad comprising elements having outwardly increasing dimensions quilted to the lining only at the elbow region, and means on the strap extensions for detachably securing the device in use.

3. An elbow protector for automobile drivers comprising an exterior covering of leather embodying a central component having opposingly curved longitudinal edges and co-extensive straps, flanking components 50 having the medial edges reversely curved with substantially straight tangentially-mergent portions, notches in the respective components for purposes of registration, the adjoining portions of said components being 55 sewn together with the free edges retrovert-

ed and hemmed, a textile material lining of corresponding contour and formation united to the covering by perimetric sewing, a pad comprising fabric elements having outwardly increasing dimensions quilted to the lining only at the elbow region, said elements extending beyond the adjoining edges of the components and snap fasteners on the straps for detachably securing the device in use.

Signed at Fox Chase, in the county of Philadelphia and State of Pennsylvania, this 25th day of June, 1931.

LEONARD BRUCKLER.
